(57) **CLAIM**

We claim the ornamental design for a handheld grater, as shown and described.

DESCRIPTION

FIG. 1 is a perspective view of the handheld grater of the present invention shown with its catch bin in a closed configuration.

FIG. 2 is a right side elevation view of the handheld grater of the present invention shown with its catch bin in a closed configuration.

FIG. 3 is a left side elevation view of the handheld grater of the present invention shown with its catch bin in a closed configuration.

FIG. 4 is a top plan view of the handheld grater of the present invention shown with its catch bin in a closed configuration.

FIG. 5 is a bottom plan view of the handheld grater of the present invention shown with its catch bin in a closed configuration.

FIG. 6 is a front elevation view of the handheld grater of the present invention shown with its catch bin in a closed configuration.

FIG. 7 is a rear elevation view of the handheld grater of the present invention shown with its catch bin in a closed configuration.

FIG. 8 is a perspective view of the handheld grater of the present invention shown with its catch bin in an open configuration.

FIG. 9 is a right side elevation view of the handheld grater of the present invention shown with its catch bin in an open configuration.

FIG. 10 is a left side elevation view of the handheld grater of the present invention shown with its catch bin in an open configuration.

FIG. 11 is a top plan view of the handheld grater of the present invention shown with its catch bin in an open configuration.

FIG. 12 is a bottom plan view of the handheld grater of the present invention shown with its catch bin in an open configuration.

FIG. 13 is a front elevation view of the handheld grater of the present invention shown with its catch bin in an open configuration; and,

FIG. 14 is a rear elevation view of the handheld grater of the present invention shown with its catch bin in an open configuration.

The broken lines in the drawings represent unclaimed features.
